5 Claims.

(Cl. 62—6)

This invention relates to refrigeration and more particularly to an apparatus and method for conditioning air or other fluids.

It is among the objects of this invention to provide an apparatus for conditioning air or other fluids in a simple and efficient manner, in such a way that an apparatus of any desired capacity may be constructed of unitary refrigerating structures of smaller size.

10 Further objects and advantages of the present invention will be apparent from the following description, reference being had to the accompanying drawings, wherein a preferred form of the present invention is clearly shown.

15 In the drawings:

Fig. 1 is a diagrammatic representation of an apparatus embodying features of my invention;

Fig. 2 is a cross-sectional view taken along the line 2—2 of Fig. 1; and

20 Fig. 3 is a diagrammatic representation of a slightly modified form of apparatus.

An apparatus embodying features of my invention includes in general a conduit or passageway 10 for circulating air or other fluids to be 25 conditioned for the enclosure or room 11. Preferably the air is circulated from the room through an intake conduit 12, and is discharged into the room through the conduit 13, the circulation of air being accomplished by means of a fan 14.

30 The passageway 10 is provided with an evaporator structure 15 which includes a plurality of evaporators 15a, 15b, 15c, 15d, etc. These evaporators may be of standard or selected unitary dimensions, and a sufficient number of evaporators 35 may be used to provide sufficient refrigerating capacity for cooling the air in the room 11.

The evaporators are placed edge to edge across the passageway 10 and preferably extend only 40 partially across, leaving a fixed air by-pass 16a.

The evaporators 15a, 15b, 15c, 15d, etc., may be connected with a plurality of refrigerant liquefying units 16a and 16b, the number and size of the units 16a and 16b being sufficient to provide 45 the necessary refrigerating capacity in the evaporators. Preferably each of the refrigerant liquefying units 16a and 16b are connected to one or more of the evaporators, so that at least one of the refrigerant liquefying units is in a closed refrigerant circulating cycle, which cycle includes 50 one or more of the evaporators and is separate from the closed refrigerating cycle or cycles of another of the refrigerant liquefying units. Thus the refrigerant liquefying unit 16a delivers liquid 55 refrigerant through the line 17 to an expansion

valve 18 from whence the expanded refrigerant flows to one or more of the evaporators, in this case to the evaporators 15b and 15d. The evaporated refrigerant from these evaporators returns through the suction line 19 to the intake 5 of the refrigerant liquefying unit in a closed circulating cycle. The other of the refrigerant liquefying units 16b delivers liquid refrigerant through the line 20 to the expansion valve 21, from whence the expanded refrigerant flows to 10 one or more of the evaporators 15a and 15c, from whence the refrigerant returns through the suction line 22 to the intake of the refrigerant liquefying unit 16b thus forming another closed refrigerant circulating cycle which is separate from 15 the closed cycle of unit 16a.

The refrigerant liquefying units 16a and 16b are provided with means whereby one unit may operate independently of another unit. To this end, a thermostat 23 is placed in the room 11 20 which operates a snap switch which governs the flow of electric current through the motor 24 of the refrigerant liquefying unit 16b. The motor 24 drives the compressor 25 which in turn delivers compressed refrigerant through the line 26 25 to the condenser receiver 27. If the condenser receiver 27 is water-cooled, a proper automatic control for governing the flow of water through the condenser (not shown) is provided, which automatic control is governed in accordance with 30 the operation of the liquefying unit, as is well known in the art. Another thermostat 28 is provided in the room 11, and this thermostat operates a snap switch which governs the electric current flowing through the motor 29 which in 35 turn operates the compressor 30. Compressed refrigerant is delivered through the line 31 to the condenser receiver 32 in a manner similar to that described with respect to refrigerant liquefying unit 16b. Thus the thermostats 23 and 28 govern 40 the operation of the refrigerant liquefying units 16a and 16b independently of each other, and this action in turn governs or varies the refrigerating effect of the evaporators 15a, 15b, 15c and 15d, in such a manner, that the refrigerating 45 capacity of at least one of the evaporators is independent of the refrigerating capacity of at least another of said evaporators.

Preferably the thermostats 23 and 28 are so calibrated that when the temperature of the 50 room 11 is lowered to a certain predetermined limit one or more of the refrigerant liquefying units is stopped with a consequent variation of the refrigerating capacity or effect of its connected evaporator or evaporators; and when the 55

temperature of the room 11 is still further lowered another one or more of the units is stopped with a consequent variation of the refrigerating capacity or effect of its connected evaporator or 5 evaporators; and thus, the refrigerant liquefying units may be stopped, step by step, as the temperature drops in the room 11 until all of the units are stopped. Conversely, as the temperature rises in the room 11 the units are started 10 step by step until all of the units are operating. Thus the refrigerating capacity or effect of the evaporator structure 15 is varied in accordance with the refrigeration requirements of room 11.

An advantage of this arrangement is that the 15 heat absorbing capacities of the evaporators and the refrigerant liquefying capacity of the installation are balanced at all times. By providing individual liquefying units for each set of evaporator surfaces, it is possible to maintain the evaporator surfaces at the proper temperatures, which in the case of an air conditioning installation, preferably are above 32° F. and below the normal dew point of the air to be conditioned.

The thermostats 23, 28, and others if desired, 25 may be grouped together at one zone in the room 11, but sometimes it may be desirable to place one or more of the thermostats at various parts of the room separate from the rest, particularly placing one or more in a zone where an abnormal 30 rise in temperature is likely to occur during a part of the day. Thus if one side of the room is likely to be subjected to the direct rays of the sun during part of the day, one or more of the thermostats 35 may be placed at that side or zone to insure some refrigeration notwithstanding that the remainder of the room does not require it.

Means may be provided for introducing fresh air into the room or enclosure 11. This means 40 may be independent of the air circulating means heretofore described or it may be incorporated therein. In Fig. 1 this fresh air intake 33 communicating with the exterior of the building is provided 45 with a fan 34 driven by an electric motor 35. The electric motor 35 may be operated by a hand switch or humidistat 36. If the control 36 is a humidistat, the setting may be so calibrated that when the relative humidity rises above a pre- 50 determined limit, the fan 34 will be caused to start or to increase its speed, and when the humidity falls below a predetermined limit the fan would be caused to stop or decrease its speed. Thus the fan 34 is made responsive to relative 55 humidity conditions in the room 11, which, in turn, depend to a large extent upon the number of people in the room. If desired hand dampers 38 may be provided as an alternative or in addition for governing the amount of fresh air introduced into the room 11.

In the modification shown in Fig. 3, similar parts are numbered with similar numbers except that 100 has been added. The operation of the evaporators, refrigerant liquefying units and 60 main fans 14 and 114 are substantially the same, but the fresh air intake has been made dependent on the air conditioning system. To this end, the fan 114 is placed on the outlet of the air conditioning passageway 110, and fresh air inlet 70 150 is connected to the suction side of the fan 114. As shown in full line in Fig. 3, fresh air conduit 150 may be connected between the air conditioning conduit 110 and the fan, or, as shown in dotted lines, the fresh air conduit 150 may be 75 connected to the intake side of the air condition-

ing conduit. In either construction, a damper 151 or 151' may be placed in the fresh air conduit, and this damper may be manually operable or automatically operable. If automatically operable, the damper may be moved or controlled by a humidistat 152 which opens and closes the damper in accordance with relative humidity conditions in the room 111.

While the form of embodiment of the invention as herein disclosed, constitutes a preferred form, 10 it is to be understood that other forms might be adopted, all coming within the scope of the claims which follow.

What is claimed is as follows:

1. In an air conditioning apparatus, an enclosure, air flow means having an outside fresh air inlet and a recirculated air inlet for air to be conditioned for said enclosure, air blowing means for circulating air through said air flow means, a plurality of refrigerant evaporators in said air flow means, refrigerant liquefying means connected to said evaporators, means automatically rendering inactive the evaporation of refrigerant in one of said evaporators while evaporation remains active in another of said evaporators in accordance with conditions in said enclosure and balancing the liquefying capacity of said liquefying means, whereby the active refrigerant temperature remains substantially constant.

2. In an air conditioning apparatus, an enclosure, air flow means for air to be conditioned for said enclosure, air blowing means connected to said air flow means, a plurality of refrigerant evaporators in said air flow means, refrigerant liquefying means connected to said evaporators, control means automatically rendering inactive the evaporation of refrigerant in a number less than all of said evaporators while evaporation remains active in the remaining evaporator or evaporators in accordance with conditions in said enclosure, the construction and arrangement being such that when said evaporators operate together they operate at a temperature to avoid freezing moisture from air on said evaporators, and when said number less than all of said evaporators is rendered inactive the remaining evaporator or evaporators are balanced with said liquefying means to operate at a temperature to avoid freezing moisture from air thereon.

3. In an air conditioning apparatus, an enclosure, air flow means for air to be conditioned for said enclosure, air blowing means connected to said air flow means, an inlet for introducing fresh air into said apparatus, a recirculated air inlet, a plurality of refrigerant evaporators in said air flow means, refrigerant liquefying means connected to said evaporators, control means automatically rendering inactive the evaporation of refrigerant in a number less than all of said evaporators while evaporation remains active in the remaining evaporator or evaporators in accordance with conditions in said enclosure, the construction and arrangement being such that when said evaporators operate together they operate at a temperature to avoid freezing moisture from air on said evaporators, and when said number less than all of said evaporators is rendered inactive the remaining evaporator or evaporators are balanced with said liquefying means to operate at a temperature to avoid freezing moisture from air thereon.

4. In an air conditioning apparatus, an enclosure, air flow means for air to be conditioned for said enclosure, air blowing means connected to said air flow means, a plurality of refrigerant

- 5 evaporators in said air flow means arranged for the flow of air in parallel in thermal contact with said evaporators, refrigerant liquefying means connected to said evaporators, control means automatically rendering inactive the evaporation of refrigerant in a number less than all of said evaporators while evaporation remains active in the remaining evaporator or evaporators in accordance with conditions in said enclosure, the 10 construction and arrangement being such that when said evaporators operate together they operate at a temperature to avoid freezing moisture from air on said evaporators, and when said number less than all of said evaporators is rendered 15 inactive the remaining evaporator or evaporators are balanced with said liquefying means to operate at a temperature to avoid freezing moisture from air thereon.
5. In an air conditioning apparatus, an enclosure, air flow means for air to be conditioned for said enclosure, air blowing means connected 20 to said air flow means, a plurality of refrigerant evaporators in said air flow means, refrigerant liquefying means including a plurality of compressors connected to said evaporators, control means automatically rendering inactive the evaporation of refrigerant in a number less than all of said evaporators while evaporation remains active in the remaining evaporator or evaporators in accordance with conditions in said enclosure, the construction and arrangement being such that when said evaporators operate together they operate at a temperature to avoid freezing moisture from air on said evaporators, and when said number less than all of said evaporators is rendered inactive one of said compressors is rendered inactive and the remaining evaporator or evaporators are balanced with said liquefying means to operate at a temperature to avoid freezing moisture from air thereon.
